US00D892092S

(12) United States Design Patent (10) Patent No.: US D892,092 S
(45) Date of Patent: * Aug. 4, 2020

(54) ANTENNA

(71) Applicant: Shenzhen 1Byone Technology Co., Ltd., Shenzhen, Guangdong (CN)

(72) Inventor: Ruishi Yang, Guangdong (CN)

(73) Assignee: SHENZHEN 1BYONE TECHNOLOGY CO., LTD., Shenzhen, Guangdong (CN)

() Term: 15 Years

(21) Appl. No.: 29/669,027

(22) Filed: Nov. 5, 2018

(51) LOC (12) Cl. 14-03

(52) U.S. Cl.

USPC D14/230

(57) CLAIM

The ornamental design for an antenna, as shown and described.

DESCRIPTION

FIG. 1 is a front perspective view of an antenna showing my new design;

FIG. 2 is a rear perspective view thereof;

FIG. 3 is a front perspective view thereof, with the side panels in an alternative position;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines illustrate portions of the antenna which form no part of the claimed design.
